UNITED STATES PATENT OFFICE.

JOHN H. BOREN, OF HAUBSTADT, INDIANA.

WATER-ELEVATOR.

SPECIFICATION forming part of Letters Patent No. 241,915, dated May 24, 1881.

Application filed March 9, 1881. (Model.)

To all whom it may concern:

Be it known that I, JOHN H. BOREN, of Haubstadt, in the county of Gibson and State of Indiana, have invented a new and Improved 5 Water-Elevator, of which the following is a specification.

The object of my invention is to provide a new and improved water-elevator which is so constructed that when the filled bucket is raised 10 an empty bucket is lowered.

The invention consists in a chute or gutter passing through the frame of the water-elevator, which chute is provided with a parallel rod a short distance above it, on each side, 15 against which rod projections on the buckets catch, thereby tilting the buckets so that their contents will flow into the chute.

In the accompanying drawings, Figure 1 is a longitudinal sectional elevation of my improved water-elevator. Fig. 2 is a cross-sectional elevation of the same. Fig. 3 is a plan view of the same.

Similar letters of reference indicate corresponding parts.

A shaft, A, is journaled in the casing B of the water-elevator, and on this shaft two rope pulleys or drums, C and C', are rigidly mounted. Two bevel-gear wheels, D and D', are also rigidly mounted on this shaft, facing each other, and 30 separated a distance slightly greater than the diameter of a bevel-gear wheel, E, mounted on the end of the crank-shaft F, and arranged at right angles to the wheels D and D'. The crank-shaft F is journaled in the upper end of 35 a swinging arm, G, pivoted to the casing B, and connected by a connecting-rod, H, with a lever, J, also pivoted to the casing B, so that the arm G can be moved to and fro by means of the lever J. A chute or trough, K, passes 40 through the casing B below the shaft A and parallel to the same, the front end, L, of this trough or chute forming a spout and projecting out of the casing B. A rod, M, is arranged parallel to each side of the chute or trough K, 45 a short distance above it. A rope or chain, N', is coiled on the drum or pulley C' from left to right, and a rope, N, is coiled on the drum or pulley C from right to left. A band or strap, O O', is attached to the lower end of 50 each rope or chain, and a bucket, P or P', is suspended from the end of the band O or O'.

These buckets are provided on opposite sides with projecting pins Q, which are at right angles to the direction of the bail R.

The operation is as follows: If the bucket P' is to be raised, the lever J is moved in the direction of the arrow a', causing the gear-wheel E on the crank-shaft F to engage with the wheel D'. If the crank S is turned from left to right, the wheel D', and consequently 60 the shaft A, will be rotated from left to right, causing the rope N' to be wound upon the drum C', whereas the rope N is unwound; but if the lever J is moved in the inverse direction of the arrow a' the wheel E will engage with the wheel D and the shaft A will be rotated from right to left, causing the rope N to be wound upon the drum C, whereas the rope N' is uncoiled. As the buckets are attached to the straps or bands O, and these bands 70 lie flat against the rods M, the bail R will be parallel to these rods; but one of the projecting pins Q will catch under the rod M, thereby 75 tilting the bucket, as shown in Fig. 2, and pouring the water into the chute K, through which it flows into the pail T, placed under the spout L.

It is plain that the empty pail will descend as rapidly as the filled pail rises, and the crank S need always be turned in the same direction. 80

Having thus fully described my invention, I claim as new and desire to secure by Letters Patent—

1. In a water-elevator, the combination, with 85 the shaft A, of the winding-drums C C', the bevel-gear wheels D, D', and E, the crank-shaft F, the swinging arm G, the connecting-rod H, and the pivoted lever J, substantially as herein shown and described, and for the purpose set 90 forth.

2. In a water-elevator, the combination, with 95 the shaft A, of the winding-drums C C', the chains N N' of the bands or straps O O', the buckets P P', provided with projecting pins Q, the chute K, and the rods M M, substantially as herein shown and described, and for the purpose set forth.

JOHN H. BOREN.
